APRON

Leonie Brehm, Detroit, Mich.

Application March 10, 1945, Serial No. 582,059

2 Claims. (Cl. 2—50)

1

This invention relates to an apron and it has to do particularly with an apron or protective covering designed to be worn by a person receiving a treatment of the hair or head, such as may be performed by establishments generally known as beauty parlors. Such treatments may include the obtaining of a wave in the hair, such as the so-called permanent wave or finger wave, or other treatments such as a wash or shampoo, or the hair may be trimmed or otherwise treated or the wave may be set.

The general object of the invention is to provide an improved protective covering which not only protects the person but which facilitates the work of the operator. In performing certain work, numerous hair pins may be employed and ordinarily the operator has the hair pins disposed on a suitable table and one or more steps and turns are required when placing the hair pins in the hair or when removing them. The hair pins are most usually of steel construction and, therefore are magnetic and one of the objects of the invention is to provide for holding a number of hair pins in a convenient location on the person receiving the treatment. To this end, the protective covering is arranged for the reception of a magnetic holding instrument. Moreover, an article such as a comb or brush or the like is frequently employed and means are provided for holding such items of equipment in a convenient place for the operator. Accordingly, many steps and turns or the like of the operator are eliminated resulting in a saving of time and more efficient work. Still further, it is an object of the invention to provide an apron which will furnish a protective cushion or pad for the person, which will cushion the apron on the neck of the customer and provide a cushion or pad for the neck when the person reclines in a chair designed for such purposes.

A protective covering constructed in accordance with the invention is disclosed in the accompanying drawings:

Fig. 1 is an elevational view of the covering applied to a person.

Fig. 2 is a rear elevational view of the covering applied to a person.

Fig. 3 is a cross sectional view taken substantially on line 3—3 of Fig. 2 showing the protective cushion or pad.

Fig. 4 is a plan view of the apron.

Fig. 5 is a perspective view of a magnetic pin holder.

Fig. 6 is a cross sectional view taken substantially on line 6—6 of Fig. 3 showing the pad construction.

Fig. 7 is a detailed view partly in section showing the magnetic holder with several pins thereon.

Fig. 8 is a view of the removable pocket.

As shown in Fig. 4 the protective covering com-

prises a major body portion 1 in the form of an apron cut out near one end as shown at 2. The cut out portion leads to a sort of rounded opening 3 designed to be passed around the neck of the wearer. This opening portion may be bounded by a suitable edging 4 which advantageously may be slightly enlarged or padded and the edgings terminate in ties 5.

The apron is designed to be applied to the person as shown in Figs. 1 and 2, with the neck of the person passing through the opening 3. The ties are drawn across the back of the neck of the person and are then brought to the front of the neck or at the throat and tied in a knot as shown in Fig. 1. The edging 4 is preferably enlarged near the mouth of the opening 3 to provide enlarged pad or cushion portions 6. These portions may be shaped somewhat of tapering form and are designed to be overlapped as shown in Fig. 3. Thus, the portions provide a pad or cushion at the back of the neck and are designed to provide comfort to the user when the user is reclining upon the usual chair designed for work of this kind. When the apron is applied to the person it preferably overlaps in the back as shown in Fig. 2, in order to provide a waterproof arrangement. Accordingly, any water which may drip from the hair or head is prevented from access to the clothing of the person. The apron may be made of suitable material, such as an oiled silk or rubberized fabric or other waterproof material.

Incorporated in the apron, either as a separate piece or integral therewith, is preferably a reinforcing structure generally illustrated at 10, shaped to fit around the opening 3 and having at least one outstanding wing 11, although, as shown herein, there are two of such wings. Each wing is provided with a pocket 12. When the apron is applied to the person the wings take a position on the person preferably at the back and advantageously substantially over the shoulder blade. This positions the pockets in a convenient location so that suitable working devices, such as a comb or brush or the like may be held therein. For purposes of sanitation, and in order to comply with sanitary requirements, a separate removable pocket 13 is provided for insertion in the pockets 12. As shown in Fig. 2 there is one removable pocket 13 illustrated and it retains a comb 14. It will be understood that a removable pocket may be used in the opposite pocket 12 at the same time. While the apron may be used on various customers the removable pocket and comb are to be removed and washed or otherwise cleansed or sterilized for individual customers. One side of the pocket, as at 15, extends beyond the opposite side 16 and the pocket is advantageously left partially open along one edge down to about the location 17. This facilitates

insertion of a working tool as shown in Fig. 2. The portion 10 may be, and preferably is, of an oiled silk or rubberized fabric.

Attached to the apron and specifically to the part 10 is at least one strap 20. As shown herein there are two of such straps. Each is attached to the body of the apron adjacent the edging of the neck 3 and adjacent the outer edge of the part 10. These are preferably located so as to be positioned near the top of the shoulder when the apron is applied as shown in Fig. 2. These straps are for the purpose of receiving pin holders. As shown in Fig. 5 the holder comprises a bar of magnetized metal 21 comprised of suitable magnetic material, preferably equipped with a suitable spring clip 22. This holder may be applied to the strap as shown in Fig. 7 with the clip engaging the strap as illustrated. A quantity of hair pins, as illustrated at 25, may be deposited in any suitable fashion or at random on the magnetic holder 21 and they are maintained magnetically in position. The holders are readily removable from the apron when such is necessary for cleaning, washing or otherwise treating the apron.

In use, the apron is applied to the person as above described and one or more magnetic holders may be attached to the straps. One or more other devices, such as a comb, may be used with its removable pocket 13. Thus, an operator may perform the necessary operations and work upon the customer without stepping, turning or reaching for articles of equipment. The comb is in a handy location and, indeed, right under the place where the work is being performed on the head or hair of the subject. When it is necessary to apply the pins to the hair they are merely picked off the magnetic holder, which is immediately available, right under the location where the work is being performed. When the pins are being removed they may again be placed upon the holder. As stated above, if the subject is to take a reclining position in a chair which may embody the usual head rest the pads 6 serve as a neck rest and, therefore, make for comfort to the customer. Moreover, the padded edging 4 together with the cushion 6 make the apron particularly comfortable from the standpoint of supporting the weight thereof while the customer is in an upright position. It is, of course, to be understood that the straps 20 and pockets 12 may be applied directly to the body portion 1 of the apron or on a separate re-enforcing structure 10 as illustrated.

I claim:

1. A protective covering adapted to be worn by a person receiving a treatment of the head or hair or the like comprising, a body sheet, said body sheet being cut out along one edge to provide a neck opening for fitting around the neck of the person, said body sheet adapted to be disposed over the shoulders and part of the body of the person, a reinforcing member mounted on the body sheet and partially surrounding the neck

opening and having a wing extending laterally from each side of the neck opening, each of said wings having a pocket therein, said wings of the supporting member being so located that when the covering is placed upon a person, the wings and the pockets thereon are positioned at the back of the person and below the shoulder, said pockets adapted to receive working tools or the like, a strap on the reinforcing member extending from a point adjacent the neck opening to a point adjacent the edge of the reinforcing member, said strap being secured at its ends and being so positioned that the same lies substantially over the shoulder when the covering is applied to the person, a holding device for hair pins in the form of a bar of magnetized metal and a spring clip on the bar arranged to engage said strap.

2. A protective covering adapted to be worn by a person receiving a treatment of the head or hair or the like comprising, a body sheet, said body sheet being cut out along one edge to provide a neck opening for fitting around the neck of the person, said body sheet adapted to be disposed over the shoulders and part of the body of the person, a reinforcing member mounted on the body sheet and partially surrounding the neck opening and having a wing extending laterally from each side of the neck opening, each of said wings having a pocket therein, said wings of the supporting member being so located that when the covering is placed upon a person, the wings and the pockets thereon are positioned at the back of the person and below the shoulder, said pockets adapted to receive working tools or the like, a strap on the reinforcing member extending from a point adjacent the neck opening to a point adjacent the edge of the reinforcing member, said strap being secured at its ends and being so positioned that the same lies substantially over the shoulder when the covering is applied to the person, said strap adapted to detachably receive and hold a clip of a holder for hair pins.
